F. R. WILLSON, OF COLUMBUS, OHIO.

Letters Patent No. 69,290, dated September 24, 1867.

IMPROVEMENT IN HARROW-TEETH.

The Schedule referred to in these Letters Patent and making part of the same.

TO ALL WHOM IT MAY CONCERN:

Be it known that I, F. R. WILLSON, of Columbus, in the county of Franklin, and State of Ohio, have invented a new and useful Improvement in Harrow-Teeth; and I do hereby declare that the following is a full, clear, and exact description thereof, which will enable those skilled in the art to make and use the same, reference being had to the accompanying drawings, forming part of this specification, in which—

Figure 1 is a side view of a harrow having my improved single plate split cultivator teeth;

Figure 2 is a bottom view of the same.

Figure 3 is a back view of a single tooth.

Similar letters of reference indicate corresponding parts.

This invention relates to an improvement in the construction of harrow-teeth, and consists in a tooth with two cultivator-wings placed one ahead of the other, made of a single steel plate of a lozenge form, by splitting the plate partly across and turning out the split parts in opposite directions, right and left, and leaving the upper side of the plate solid, to be fastened to the harrow-frame by screw-bolts, which may be secured to the top of the plate with a cast-iron head upon it, or in any other suitable manner.

This method of making a steel harrow-tooth with independent wings or flanges spreading right and left, one ahead of the other, is much simpler and cheaper than the ordinary mode of construction, with the wings united at the throat in front, and spread right and left opposite each other, like a cultivator. Welding is not necessary to form the tooth when made in this manner, as the plate is split merely, and the wings bent outward as desired, and both wings present edges in front, which are more easily sharpened and kept in good working order than the throat of an ordinary cultivator-tooth. The tooth made in this manner presents a sharp, single edge to the soil, and will cut and penetrate it when stiff and hard much more easily than an ordinary cultivator-shaped tooth, while the wings, placed one in front of the other, will act more effectively as pulverizers of the earth.

aa are independent wings or curved flanges, shaped like a plough mould-board on one side of a common cultivator. The wings aa are formed by turning to the right and left the heels or lower back parts of two divisions of a steel plate, which is split partly across from the lower side, as shown clearly in fig. 1. To fasten the winged tooth to a harrow-frame, a head, c, may be cast on the upper part, having also the heads of two screw-bolts, dd, cast in solid, as shown in the drawings, or the upper part of the plate may be turned over to form a flat flange, through which the screw-bolts may pass, to secure the tooth to the frame. In order to secure the greatest strength and resisting power against lateral pressure, the teeth are made in sets, with right and left front wings, so that the front wings shall turn outward when placed on a harrow, as shown in fig. 2.

Having thus described my invention, what I claim as new, and desire to secure by Letters Patent, is—

Making a harrow-tooth of a single steel plate, split part of the way across, with independent wings aa, placed one ahead of the other, substantially as shown and described.
